UNITED STATES PATENT OFFICE

130,048

DESIGN FOR A CABINET FOR AUTOMATIC PHONOGRAPH

Henry T. Roberts, Cuba Township, Lake County, Ill., assignor to J. P. Seeburg Corporation, Chicago, Ill., a corporation of Illinois

Application February 20, 1941, Serial No. 99,132

Term of patent 14 years

To all whom it may concern:

Be it known that I, Henry T. Roberts, a citizen of the United States, residing at Cuba Township in the county of Lake and State of Illinois, have invented a new, original, and ornamental Design for a Cabinet for Automatic Phonograph, of which the following is a specification, reference being had to the accompanying drawing forming part thereof.

Fig. 1 is a plan view of a cabinet for automatic phonograph embodying my new design; Fig. 2 is a front elevation thereof; and Fig. 3 is a side elevation thereof.

I claim:

The ornamental design for a cabinet for automatic phonograph, as shown.

HENRY T. ROBERTS.
